G. W. BRIGGS,
ELECTRIC STREET CAR INDICATOR.
APPLICATION FILED OCT. 3, 1916.

1,323,672.

Patented Dec. 2, 1919.

UNITED STATES PATENT OFFICE.

GEORGE W. BRIGGS, OF ST. JOSEPH, MISSOURI.

ELECTRIC STREET-CAR INDICATOR.

1,323,672.

Specification of Letters Patent.

Patented Dec. 2, 1919.

Application filed October 3, 1916. Serial No. 123,568.

To all whom it may concern:

Be it known that I, GEORGE W. BRIGGS, a citizen of the United States, residing at St. Joseph, in the county of Buchanan and

5 State of Missouri, have invented certain new and useful Improvements in Electric Street-Car Indicators; and I do hereby declare the following to be a full, clear, and exact description of the invention, such as 10 will enable others skilled in the art to which it appertains to make and use the same.

This invention relates to new and useful improvements in an electric street car indicator and has for one of its objects, the provision 15 of a device of this character, which shall be simple, durable and efficient, and which may be manufactured and sold at a comparatively low cost.

Another object of this invention is to 20 provide a casing secured within a car and having a window therein and a pair of rollers on which is mounted an apron carrying or bearing the names of streets or stations which appear along the path of travel of the 25 car and the name of street or station being approached by the car is adapted to be brought in rear of the window, whereby passengers upon the car may determine the street or station being approached.

30 A further object of this invention is to provide a pawl and ratchet mechanism attached to one of the rollers, whereby the rollers may be rotated to cause the apron to move, bringing the name of the station or 35 street in view in rear of the window upon approach of the street or station by the car.

A still further object of this invention is the provision of an automatic electrical operated means attached to the pawl and 40 ratchet mechanism and adapted to operate the pawl and ratchet mechanism upon approach of each street or station.

With these and other objects in view as 45 will become more apparent as the description proceeds, the invention consists in certain novel features of construction, combination and arrangement of parts as will be hereinafter more fully described and claimed.

50 For a complete understanding of my invention, reference is to be had to the following description and accompanying drawing, in which:—

Figure 1 is a longitudinal sectional view 55 of an electric street car indicator, constructed in accordance with my invention,

Fig. 2 is a plan view of trolley poles used in connection with the indicator, and

Fig. 3 is a sectional view taken on the line 3—3 of Fig. 1.

60

Referring in detail to the drawing, the numeral 1 indicates a casing having an opening 2 at one end thereof which is closed by a glass plate 3 providing a window. Journaled in each end of the casing 1 are shafts 4 and 5 on which are mounted rollers 6 and 7. Secured upon the rollers 6 and 7 is an apron 8 having printed or otherwise applied thereon names of stations or streets occurring along the line of travel or a car. The 70 apron is wound from the roller 7 and upon the roller 6 by means which will be herein-after more fully described. The apron 8 is first rolled upon the roller 7 by means of a crank 10 upon the shaft 5. Before the apron 75 passes from the roller 7 onto the roller 6, it is guided rear of the window by means of a pair of relatively spaced guide rollers 11.

An operating lever 12 is journaled on the shaft 4 and depends downwardly through 80 an elongated slot 13 in the casing and has its lower end provided with an elongated slot 14. A dog 15 is pivoted to the lever 12 and is normally held in an engagement with a ratchet wheel 16 by means of a spring 17. 85

The ratchet wheel 16 is keyed or otherwise secured to the shaft 4 for rotating the roller 6 to wind the apron thereon. A suitable bracket 17 is located adjacent the casing and upon the under side thereof and has mounted thereon a solenoid 18. One end of the bracket 17 is bent at right angles and aper-tured to receive an arm 19 which is pivoted to the elongated slot 14 of the operating lever 12. The arm 19 has secured to the free 90

end thereof an armature plate 20 which is adapted to be attracted by the solenoid 18 when energized to move the arm 19 in the direction of the solenoid to rock the operating lever 12 which rotates one of the rollers, 100 causing the apron to wind thereon and bring the next adjacent name of station or street in the rear of the window upon the car ap-105 proaching the corresponding street or sta-tion. A coil spring 21 is mounted on the arm 19 for normally returning same to its normal position after the armature plate 20 has been released by the solenoid 18.

In applying this invention to a street car or the like, the casing is secured within the 110 car in any suitable manner and has the bracket 17 located adjacent thereto. The

trolley pole 22 of the car (not shown) is provided with an auxiliary guide wheel 23 which is adapted to engage contacts 24 carried by the trolley wire 25 and connected 5 upon the trolley wire at points before reaching each of the intersecting streets or stations arranged along the line of travel of the car. The auxiliary trolley wheel 23 is connected to the solenoid 18 by a conductor 10 26 and the solenoid is connected to a ground 27 by a conductor 28 whereby when the auxiliary trolley wheel 23 engages one of the contacts 24 located upon the trolley wire 25, the solenoid 18 is energized attracting the 15 armature plate 20 causing the arm 19 to rock the operating lever 12 which in turn rotates the roller 6, causing the apron 8 to wind thereon and bring the name of the station or street in view through the window 20 of the street or station which is being approached.

While I have shown and described the preferred embodiment of my invention, it will be understood that minor changes in 25 construction, combination and arrangement of parts may be made without departing

from the spirit and scope of the invention as claimed.

Having thus described my invention, what I claim is:—

A street indicator including a casing having rollers journaled therein supporting an apron, a lever pivotally mounted and extending through the casing, a pawl and ratchet mechanism associated with the lever 30 35 and one of the rollers, a bracket located adjacent the casing and having one end apertured and disposed at right angles thereto, an arm slideable in the apertured end of said bracket and pivoted to the lever, an electrical means carried by the bracket for operating the arm in one direction, a pin secured to the arm, and a spring interposed between the apertured end of the bracket and said pin for returning the lever to its 40 45 initial position.

In testimony whereof I affix my signature in presence of two witnesses.

GEORGE W. BRIGGS.
